UNITED STATES PATENT OFFICE.

SAMUEL E. HITT, OF ELYRIA, OHIO.

DISAPPEARING TURRET.

1,351,383.

Specification of Letters Patent. Patented Aug. 31, 1920.

Application filed March 27, 1918. Serial No. 224,962.

To all whom it may concern:

Be it known that I, SAMUEL E. HITT, a citizen of the United States, residing at Elyria, in the county of Lorain and State of Ohio, have invented certain new and useful Improvements in Apparatus for Army use in Defensive Warfare, hereinafter called Disappearing Turrets, of which the following is a specification.

10 The world war seems to demonstrate that present methods of trench warfare have been so extensively developed that they are not likely to be superseded by radically different methods during this war and therefore that any steps taken to make our trenches safer, are in the right direction. Before a charge by the enemy, the first line trench is generally subjected to a heavy bombardment, and more or less leveled.

15 20 The men are thus either driven out or lost, so that when the enemy arrives there is not a sufficient force left to hold it.

An object of my invention is to provide a turret for machine gunners located near the trench, strong enough to withstand ordinary bombardment, to be in readiness in case of attack.

25 30 A further object of my invention is to provide a turret with a floor door opening into an underground passageway connecting to the nearest trench.

A further object of my invention is to provide a turret which can be easily operated, raised to firing height, or lowered to ground level out of sight, as desired.

35 40 A further object of my invention is to provide a turret which can be covered with such earth or other material as shall make the turret practically invisible to the enemy in daytime.

A further object of my invention is to provide a turret which can be raised or lowered by the operator from within by manual power.

45 50 A further object of my invention is to provide a turret which can be turned horizontally in either direction without limitation by the operator from within by manual power.

A further object of my invention is to provide a turret in which both the vertical

and horizontal movements can be conveniently controlled by the operator at the same time.

A further object of my invention is to provide a counterweight for the turret so that it can be manipulated with minimum effort.

A further object of my invention is to provide a casing for the turret for protection and also to act as a guide.

A further object of my invention is to provide a turret which is gas tight as far as practicable.

A further object of my invention is to provide a turret and casing which can be made in a number of parts to facilitate transportation and erection.

A further object of my invention is to provide a flexible apparatus, not easily put out of order, but easy to repair.

A further object of my invention is to ventilate the turret without in any way endangering its occupants.

In the accompanying drawings: Figure 1 is a sectional plan showing relative position of turret and trench. Fig. 2 is a vertical section on the line *t t* of Fig. 1. Fig. 3 is a vertical section on the line *u u* of Fig. 1. Fig. 4 is a sectional plan of the turret on the line *w w* of Fig. 3. Fig. 5 is a front view of the turning and elevating mechanism. Fig. 6 is a side view and partial section of the turning mechanism on the line *y y* of Fig. 5. Fig. 7 is a side view and partial section of the elevating mechanism on the line *z z* of Fig. 5. Fig. 8 is a partial section of the turret and connecting rod on the line *t t* of Fig. 1. Fig. 9 is a plan of the carriage. Fig. 10 is a sectional view of the caster on the line *x x* of Fig. 4. Fig. 11 is a partial section of the track and carriage mounted on wheels with flat treads. Fig. 12 is a partial plan of the turret floor, showing the trap door closed. Fig. 13 is a part vertical section of the turret and trap door locked in closed position. Fig. 14 is a part vertical section of the turret and ventilator as mounted. Fig. 15 is an elevation of the same.

In Fig. 1, 1 is the turret connected by the passageway 2 with the trench 3. 4 is a

branch chamber for the counterweight. The turret 1 is movable within the casing 5.

In Fig. 2, the turret 1 is shown in its highest position, with a gunner using a machine gun. A ladder 6 hangs from the turret 1 and is accessible from steps 7 placed in the passageway 2.

In Fig. 3, the turret is shown in its lowest position, the top of the turret being level with the ground. The top of the turret 1 is recessed and is filled with earth 8 similar to the adjoining ground to make it practically invisible to the enemy. The turret shell 1, being made of steel plate three-eighths of an inch thick, is quite heavy and is balanced by the connecting rod 9, balance beam 10 and counterweight 11. The weight of the turret shell 1, beam 10 and counterweight 11 is supported by the pin 12, bearing 14, block 15 and foundation 16. The door 17 is hinged at 18 and locked by a bar 19 and is ordinarily left closed, the gunners shooting through the port holes 20, which can also be closed by a coverplate 21 and locked by fingers 21^a, which engage bolts 21^b and thumb nuts 21^c. The turret shell 1 is surrounded by a casing 5 buried in the ground, with the top of the casing at ground level and supported by timbers 22 or other suitable framework. The turret is turned to the right or left by the horizontal handwheel 24 and is raised or lowered by the vertical hand wheel 25. To accomplish this purpose, a combination circular track and internal gear 26 is secured inside the casing 5 at the bottom and on this track is mounted the carriage 27, shown in Fig. 9.

The turning and elevating mechanism is shown more in detail in Figs. 5, 6, 7 and 9 where the carriage frame is seen to consist of two bars 28 separated by castings 29, 30 and 31 which carry track wheels 32 that run upon the circular track 26. The hand wheel 24 is mounted on a shaft 33 and is held in place by brackets 34 and 35. The upper portion of the shaft 33 is round on account of the hand wheel 24, bearing 34 and stuffing box 36, and is square below the turret floor 37. The square portion 38 of the shaft passes through the sleeves 39 which turn in bearings 40 in bracket 30, and passes also through the pinion 41, held between the sleeves 39, and engaging with the internal gear 42 on the track 26. It is apparent that the motion of the hand wheel 24 is transmitted through shaft 38 to pinion 41 which rolls upon the stationary gear 42, giving rise to motion of the carriage 27 which is further transmitted to the turret shell 1, by the lugs 43 engaging the guides 44 mounted on the turret shell 1. To raise the turret, the hand wheel 25 is turned clockwise and to lower, counterclockwise. The hand wheel 25 is mounted on the bracket 45 and carries the pinion 46 which

engages the rack 47 on the shaft 48 which is securely fastened to bracket 29 by one or more keys 49 and 50. The shaft 48 is necessarily mounted with considerable play or flexibility. The key 50 is provided to carry 70 the load and the key 49 for safety in case the key 50 should fail. The track wheels 32 are shown with a V tread in Figs. 3, 6, 7 and 9, but are preferably provided with a flat tread 91, wider than the track 26, as 75 shown in Fig. 11, to allow enough lateral motion of the carriage to compensate for irregularities in the motion of the turret. When the operator has raised or lowered the turret 1, to the desired elevation, it is 80 locked in position by turning the small hand wheel 51 on the set screw 52. The track wheel pins 53 are arranged for easy removal from the inside.

The stuffing boxes 36 act both as guides 85 for the shafts 33 and 48 and also to keep the turret chamber gas tight. The floor opening 54 shown in Fig. 4, is provided with a trap door 92 shown in Figs. 12 and 13, hinged at 86, which is also made gas tight 90 and furnished with a fastening device operable from within, for cases of emergency, consisting of a handle bar 87 mounted on top of the door 92 in bearings 88 and carrying pawls 89 which engage lugs 90 on the 95 shell 1 when the handle is thrown over against the shell as shown in Fig. 13.

In Fig. 8, the construction of the turret is shown more in detail. The ventilator holes 55 in the side shell 56 are located directly under the recess top 57 and are spaced to match similar holes in the movable guard angle 58, which is held in place by clips 59. This guard angle 58 is bent up to shield the holes 55 so that the occupants 100 of the turret cannot be shot through these openings with enough clearance between the angle and top plate 57 to equal the ventilating area of the holes 55. In case of approaching gas, the guard angle 58 can be 110 shifted by hand until the holes 55 are completely covered. As shown in Figs. 14 and 15, the ventilator holes 93 in the guard angle 58 are spaced to match the holes 55 in the turret shell 56. The guard angle 58 has a sliding fit in the shell 56 and can easily be shifted by hand. The guard angle 58 is supported by rollers 94 which turn on pins 95 carried by the clips 59 which are secured to the shell 56 by the rivets 96.

The guard angle 58 is moved by hand until the pin 97 engages the clip 59, when the holes 93 all come opposite or match the holes 55 in the shell 56 and the ventilator is open.

When it is desired to close the ventilator, the guard angle 58 is moved by hand in the opposite direction until the pin 98 engages the clip 59, when the holes 93 in the guard angle 58 are midway between and clear of the 125 130

holes 55 in the shell 56 and the ventilator is closed. Corner braces 60 are provided between the shell 56 and the top plate 57, to prevent the top plate from giving way in case of external pressure as from a hand grenade. As nothing of this kind could be made to withstand the impact of heavy projectiles, the gunners only man the turret in times of action. On account of the small area of the turret and its earth covering, it is probable that few of them will be put out of commission during a bombardment. The turret shell 56 is supported by the floor plate 37, floor beams 61 and cross beams 62, at the center of which is secured the bearing 63 for the pin 64, integral with the yoke 65 for the pin 66 which has a bearing in the upper end of the connecting rod 9. The turret 1 pivots on the pin 64 for horizontal rotation, the vertical load being transmitted through ball bearings 67 to reduce friction and the manual power required for turning. The lower end of connecting rod 9 carries the yoke 68 and pin 69 which is supported by suitable brackets 70 on the balance beam 10. As shown in Fig. 3, the counterweight 11 is suspended from the other end of beam 10 by suitable pin connection 71.

In Fig. 10, the caster roller has a cushion tire 72, preferably of leather, center 73, pin 74, yoke 75, stem 76, threaded collar 77, spring 78, washer 79, mounted in the casing 80, bonnet 81 and cap 82. The casing 80 is mounted in the turret shell 56 with tap bolts 83 so that it can be removed easily from the inside. Four of these casters are placed 90 degrees apart as shown in Fig. 4, one set near the bottom of the turret and one set near the center, as shown in Fig. 3.

The operation of my invention is as follows: on receiving orders, the gunner and gunner's mate or other assistant, pass from trench 3 to passageway 2, mount the stairs 7, climb the ladder 6, enter the turret through the floor opening 54, closing the door after them, the operator, manning the hand wheels 24 and 25 turning the turret to bring one of the port holes 20 to bear upon the enemy's position and raising the turret to the desired elevation locks the turret with the hand wheel 51, whereupon the gunner opens the port hole 20, inserts his machine gun, and starts firing. When firing ceases, the turret is lowered and turned to bring the ladder opposite the steps 7.

As long as the turret casing 5 remains vertical and the turret floor 37 horizontal, it is not necessary to lock the turret against accidental turning, but in case they should get tilted, the weight of the men might have a tendency to start the turret turning, and in that case the turret can be locked against horizontal rotation by the set screw 84 and hand wheel 85.

I have herein described and shown what I consider the best manner of making my invention, consisting of a disappearing bomb proof turret for machine gunners that can be quickly operated by one man and if necessary, by the gunner himself, by manual power. One of the principal advantages of this construction herein shown, is that owing to the hand wheels being placed at one side, the central space in the turret is clear for the use of the gunner.

When an army expects to use a trench for some time, the turret casing 5 can be set in concrete. It is considered ordinarily, that concrete should not be used, so that the casing can be easily taken up and removed to another location.

For the information of those wishing to build my invention, the turret is designed with an outside diameter of six feet, four and one-half inches and a height inside of six feet, six inches, with three-quarters of an inch clearance between turret and casing, making the inside diameter of turret casing six feet, six inches, the casing having a depth of eight feet.

If found advisable from experience gained in the field, the clearance between the turret and the casing can be increased to two or three inches and the casters made with longer springs to suit.

I claim:

1. In apparatus for defensive warfare, a manually operated turret for machine gunners consisting of a cylindrical metallic casing embedded in the ground, a cylindrical metallic turret chamber movable within the said casing, counterbalance means for the said turret chamber, a supporting track mounted on the said casing, a carriage to run on the said track, means for preventing relative rotative movement of the turret chamber and carriage, a supporting rod with a rack mounted on the said carriage, a hand wheel and a pinion engaging the said rack mounted within and on the said turret chamber for the purpose of raising and lowering the same, and means for locking the said hand wheel to hold the said turret chamber at any desired elevation, substantially as specified.

2. In apparatus for defensive warfare, a manually operated turret for machine gunners consisting of a cylindrical metallic casing embedded in the ground, a cylindrical metallic turret chamber movable within the said casing, counterbalance means for the said turret chamber, a supporting track mounted on the said casing, a carriage to run on the said track, means for preventing relative rotative movement of the turret chamber and carriage, an annular gear mounted on the said casing, a horizontal hand wheel mounted on and within the said

4
turret chamber upon a vertical shaft extending through the said carriage, the said shaft carrying a pinion which engages the said annular gear for the purpose of turning the said carriage and turret chamber relatively to the casing and ground, substantially as specified.

In testimony whereof I affix my signature in the presence of two witnesses.

SAMUEL E. HITT.
